UNITED STATES PATENT OFFICE.

CHARLES D. ARMSTRONG, OF JEFFERSONVILLE, INDIANA.

STEAM-ENGINE.

SPECIFICATION forming part of Letters Patent No. 593,634, dated November 16, 1897.

Application filed September 16, 1896. Serial No. 606,004. (No model.)

To all whom it may concern:

Be it known that I, CHARLES D. ARMSTRONG, a citizen of the United States, and a resident of Jeffersonville, in the county of Clark and State 5 of Indiana, have invented certain new and useful Improvements in Steam-Engines, of which the following is a specification, reference being had to the accompanying drawings, forming a part thereof, in which similar 10 letters of reference indicate corresponding parts wherever found throughout both views.

This invention relates to steam-engines; and the objects thereof are to provide an improved device of this class which involves 15 simplicity of construction and operation and in which the greatest possible efficiency or working power is secured with a minimum supply of steam; and with these and other objects in view the invention consists of the 20 construction, combination, and arrangement of parts hereinafter described and claimed.

The invention is fully disclosed in the following specification, of which the accompanying drawings form a part, in which—

25 Figure 1 is a plan view of my improved engine, and Fig. 2 a section on the line 2 2.

In the practice of my invention I provide a suitable frame, centrally of which and at the opposite sides thereof are mounted two cylinders A and A², and said cylinders are parallel and are adapted to admit of the alternating induction of steam into each through the steam-pipes a and a², which in practice are connected with the same supply-pipe, which 30 is not shown. These cylinders are preferably open at their ends or are not provided with heads in the usual manner, and in each cylinder there are two pistons B and B², which are connected by piston-rods C with cranks D, 35 which are connected with the principal shafts E and E² of the engine, which are mounted at the opposite ends of the main frame thereof, said shafts being provided with one of the cranks D at each end, as clearly shown in 40 Fig. 1.

45 On each of the principal shafts E and E² is keyed or otherwise secured a beveled gear-wheel F, each of which operates in connection with a beveled pinion G, said pinions being firmly secured to a shaft H, which extends longitudinally of the frame, and by reason of this construction the two main shafts

E and E² must revolve together and these beveled gear-wheels and their pinions must be so adjusted that their action in producing 55 rotation of the main shafts and the reciprocating motion of the pistons shall harmonize with the movement of the engine itself.

On one of the two principal shafts is a fly-wheel K, which serves the same purpose as 60 the fly-wheel of an ordinary engine, and on the other is a pulley L, by means of which the power of the engine is transmitted as may be desired, and connected centrally with each of the cylinders A and A² is a steam-chest M, 65 in each of which is placed a valve m, which is adapted to control a passage O into the cylinder and another passage O², which communicates with the exhaust-pipe O³, and said pipes O³, one of which is provided for each 70 steam-chest, communicate with a main exhaust-pipe O⁴, and each of the valves m is controlled by a valve-rod P, each of which connects with a crank P², secured to one end of a suitably-mounted shaft P⁸, the other end of which is provided with another crank P⁴, to which is secured a pitman or crank rod P⁵, and one of these pitman or crank rods is connected with an eccentric R on the main shaft 75 E and the other with a similar eccentric R² on the main shaft E².

The engine is operated by admitting the steam between the pistons of each cylinder alternately, thus successively forcing the pistons in each cylinder apart and imparting the 85 motion through the various connections to the main shafts E and E², and the connections are so arranged that when the pistons in one cylinder are at the limit of their inward movement those in the other cylinder 90 are at the limit of their outward movement, and in this way the forcing apart of each pair of pistons brings the other pair back into proper position for the next introduction of steam, and both the induction and the exhaust valves may be worked or operated by 95 any method now in use, according to convenience, and any desired form of governor may be employed.

By admitting the steam between two pistons, as herein described, the same clearance serves for both, and in this way there is less waste than in any other method of working an equal amount of steam, and by taking

from the cylinder-head the reactionary pressure of the steam and throwing it on a pair of pistons moving at the same time in opposite directions all strain is removed from the 5 cylinder and there is no tendency to work it loose or to force it out of its alinement.

Another advantage consists in the fact that the steam, when permitted to expand in opposite directions at the same time, undergoes 10 a more complete and rapid expansion, thus tending, as the tests show, to promote economy and to quicken the stroke, and the best results will be obtained when the valves are so set as to admit the steam alternately between each pair of pistons as nearly as possible at the precise moment when the pistons between which it is admitted are at the 15 limit of their inward stroke or nearest to each other and are just ready to begin to recede 20 or to begin their outward movement.

My improved engine is perfectly adapted to accomplish the result for which it is intended, and it is evident that changes in and modifications of the construction herein described may be made without departing from the spirit of my invention or sacrificing its 25 advantages.

Having fully described my invention, I claim as new and desire to secure by Letters 30 Patent—

The herein-described steam-engine comprising the combination with a suitable frame

of two parallel cylinders mounted thereon and a main shaft at each end thereof, a piston-rod mounted in each of said cylinders, 35 said piston-rods being connected with cranks secured to the opposite ends of the adjacent main shaft, and the pistons in the other ends of said cylinders being provided with piston-rods which are connected with cranks secured to the opposite ends of the other main shaft, and each of said main shafts being provided with a beveled gear-wheel, and a rod mounted longitudinally of the frame and provided at its opposite ends with a beveled 40 gear whereby the main shafts revolve together, and each of said cylinders being provided with a steam-chest arranged centrally thereof, and with means for admitting steam 45 thereinto and into the cylinders, said means consisting of a valve, one of which is in operative connection with one of the main shafts, and the other with the other main shaft, substantially as and for the purpose set forth.

In testimony that I claim the foregoing as my invention I have signed my name, in presence of the subscribing witnesses, this 11th day of September, 1896.

CHARLES D. ARMSTRONG.
